UNITED STATES PATENT OFFICE.

LOUIS E. GOLLY, OF BROOKLYN, NEW YORK.

POWER-ACTUATED PNEUMATIC HAMMER.

1,184,687.

Specification of Letters Patent.

Patented May 23, 1916.

Application filed May 5, 1911. Serial No. 625,323.

To all whom it may concern:

Be it known that I, LOUIS E. GOLLY, a citizen of the United States, residing at Brooklyn, county of Kings, State of New York, have made a certain new and useful Invention in Power-Actuated Pneumatic Hammers, of which the following is a specification.

The invention relates to hammers or similar tools in which the hammer blow is delivered under the influence of air compression, and wherein the operating part which delivers the hammer blow is withdrawn by suction or rarefaction of air into position to enable it to deliver its blows.

The object of the invention is to provide a construction which is simple and efficient in operation, for pneumatically operating hammers or other devices by the air compressing and rarefying action of a piston operating in a cylinder or tube.

A further object of the invention is to provide a device or tool of the character referred to which is economical to manufacture, and capable of easy and ready application to its work, and may be easily controlled in its operation.

A further object of the invention is to provide a tool or device of the nature referred to wherein the power exerted in delivering the hammer blow of the instrument may be regulated.

Other objects of the invention will appear more fully hereinafter.

The invention consists substantially in the construction, combination, location and relative arrangement of parts, all as will be more fully hereinafter set forth, as shown in the accompanying drawing, and finally pointed out in the appended claims.

Referring to the accompanying drawing, and to the various views and reference signs appearing thereon,—Figure 1 is a view in suction or rarefaction of air into position to pressing and rarefying action of a piston central longitudinal section showing a construction of tool or device, in its simplest form, embodying the principles of my invention. Fig. 2 is a similar view, showing a modified arrangement embodying the principles of my invention, and the provision of means for controlling the hammer action of the device. Fig. 3 is a broken view in plan of a portion of the working end of the device shown in Fig. 2. Fig. 4 is a view partly in plan and partly in longitudinal

central section showing a slightly modified arrangement of certain of the details of the device shown in Fig. 2.

In carrying out my invention, and as fundamental characteristics thereof, I employ a cylindrical tube in which operates a piston, being reciprocated longitudinally in said cylinder in any suitable or desired manner. Also operating loosely in said cylinder is a plunger constituting the hammer. The action of the piston in rarefying and compressing atmospheric air within the cylinder or tube, is employed in carrying out my invention, for withdrawing the hammer or plunger from its work, and in causing said hammer or plunger to deliver its hammer blow. In the more refined embodiments of the broad idea of my invention, means are provided for controlling the rarefying or suction and compressing action of the piston as regards the influence exerted thereby upon the plunger or hammer. But in its broadest scope, as defined in the claims, my invention is not to be limited or restricted to these refinements.

In Fig. 1, I have shown the simplest form of embodiment of my invention, wherein 5 designates a cylinder in which operates a piston 6, and a plunger or hammer 7, the piston and plunger fitting loosely within the cylinder. A shank 8, of a tool or other device to be actuated, is inserted into one end of the cylinder 5, in line with the cylinder and hammer, and in such relation, that the hammer or plunger when operated, delivers its hammer blow thereon. A convenient arrangement is shown wherein the cylinder 5 is provided with a reduced extended portion 9 at one end thereof, through the bore of which the shank 8 of the tool extends slightly into the cylinder 5 and in position to receive the hammer blow of the plunger 7.

The piston 6 may be reciprocated in the cylinder 5 by any suitable power actuated devices. As an exemplification of an operative embodiment of means to this end, I have shown a piston rod 10, connected to the piston at one end and to an eccentric strap 11, at its other end, said eccentric strap operating on an eccentric 12, carried by a driving shaft 13, the latter being driven by any convenient arrangement of power mechanism.

By reason of the loose fitting of the plunger 7, and piston 6, in the cylinder, more or

less air is confined to a greater or less degree in the space between the proximate or juxtaposed inner surfaces of the piston and the plunger during the out-stroke of the piston. 5. ton, and a greater or less degree of rarefaction or suction is created in this space during the instroke of the piston. By reason of the rarefaction due to the suction action thus created, the plunger 7 is withdrawn inwardly 10 away from the working end of the cylinder, that is, away from the tool to be operated; and when the piston moves outwardly, the compression of the air in the space between the plunger and the piston is exerted upon the plunger, tending to drive it 15 forcibly toward the working end of the cylinder, so as to deliver a hammer blow upon the end of the tool shank arranged to receive the blow. Thus it will be seen that 20 a body of air is maintained in the cylinder between the piston and the plunger, this air being compressed in the outstroke of the piston, and utilized to cause the plunger to deliver its hammer blow, and being rarefied 25 during the in-stroke of the piston to create a suction action which draws the plunger inwardly into the cylinder preparatory to delivering its succeeding hammer blow. The 30 operation is exceedingly simple and by operating the hammer or plunger by suction and compression, I avoid and prevent the crystallizing action upon the parts of the apparatus due to the percussive action of devices of this nature.

35 Another and most important advantage is that I avoid the shock and vibration imparted to workmen in the use of the device and which would otherwise be imparted in the practical operation of the instrument, 40 particularly where the piston is operated at a high rate of speed to cause the hammer or plunger to deliver several hundred or thousand hammer blows per minute.

It may sometimes be desirable to provide 45 means for controlling the operation of the plunger or hammer, that is, of controlling the compressing and rarefying action of the piston, and supply and exhaust of air to and from the space between the piston and the 50 plunger or hammer.

In Fig. 2, I have shown one form of means for accomplishing this result. In this case the cylinder 14 is arranged in line with the piston 15, which reciprocates therein. The hammer or plunger 16 also operates within the cylinder, the piston and plunger being fitted to reciprocate smoothly and easily through the bore of the cylinder. The working end of the cylinder is provided with an opening or bore to receive the shank 17 of the tool upon which the plunger delivers its hammer blow. The cylinder is provided with lateral ports at a convenient point in its length indicated at 18. Surrounding the cylinder is a control sleeve 19,

capable of longitudinal sliding movement upon the cylinder 14. A spring 20, is interposed between a shoulder 21, on the cylinder, and a coöperating shoulder 22, formed on the sleeve 19, the tension of the spring normally tending to maintain the sleeve pressed endwise against the shoulder 23, on a fixed part of the casing. The interior of the sleeve 19, is provided with a surface 50 in which is formed a port opening 24, which port normally registers with the ports 18. When however, the sleeve is shifted endwise against the action of spring 20 the surface 50 closes the ports 18. The port 24, in the sleeve, communicates with the outer air, and when the sleeve is in the normal position shown in Fig. 2, the ports 24 and 18 are in registration with each other. It is obvious that under these circumstances the interior of the cylinder is freely open to the outer air through said registering ports, and consequently reciprocations of the piston under these conditions do not create substantial compression or suction action and the hammer or plunger 16 in such case remains 90 idle. When, however, the port 18 is closed by the port 24 being carried out of register with it, by shifting the sleeve 19 endwise against spring 20, then the rarefying or suction and compressing operations take place in the cylinder by reciprocation of the piston 95 therein with consequent proper operation of the hammer or plunger 16.

It may sometimes be desirable to adjustably regulate the stroke of the plunger or hammer 16. A simple method of accomplishing this is shown in Fig. 4 wherein the cylinder 14 is provided with a series of ports 25, 26, 27 spaced suitable distances apart, lengthwise of the cylinder, and the sleeve 19 is provided with coöperating ports 28, 29 and 30. The port 28 is of a size corresponding to and coöperating with the cylinder ports 25, as shown in Fig. 4, of the drawing. When the ports 28 and 25 are in register 100 with each other, the ports 26—29 and 27—30 are also in register with each other, and consequently the suction and compression action of the piston 15, so far as it is effective on the hammer or plunger 16, is applied 105 only in the space between the port 25, and the plunger 16, since the air exhaust through the ports 27, 26 and 25 during the outstroke of the piston prevents compression, until after the piston passes beyond the port 25, 110 in such outstroke, thereafter the compression of the body of air confined between the advancing end of the piston; and the proximate end of the plunger takes place, causing 115 the latter to deliver a short hammer blow. In case the piston does not pass the port 25 in its outstroke then, under the conditions stated there will be no operation of the hammer. If now, the sleeve 19 is shifted 120 endwise against the action of spring 20 until 125 130

port 28 is carried out of register with port 25, the ports 29 and 26, still remain in registering relation, and for this purpose, I make the port 29, of substantially double the area of port 26, so as to maintain register relation therewith after the port 25, has been closed. For the same reason the port 30, is made three times the area of ports 27—26 or 25 so as to maintain registration with port 27 after port 25 is closed and also after port 26 is closed. The closing of port 25, will then provide a larger space or area in the cylinder in which suction and compressing actions take place and hence a heavier blow 15 and a longer stroke is delivered by the plunger. The compression and suction action and the length of stroke of the plunger is still further increased by closing the port 26, by still further shifting the sleeve, with 20 the ports 30 and 27 still in register. The passages 31 afford communication from the outer air to the several ports, and the rings or surfaces 32 serving as valves to close the ports 25, 26, 27 according as the sleeve is 25 shifted.

It may be desirable to cause axial movement of the tool in the performance of its work, and according to the character of the work to be performed. To accomplish this 30 result, I propose to employ the sleeve 19 which in the use of the apparatus is grasped by the hand of the workman. The cylinder 14 is mounted for axial rotative movement, and a finger 33 on the sleeve engages in a 35 seat or a groove 34, at a convenient point in the exterior surface of the cylinder or the tool-head thereof. By rotating the sleeve, the tool and cylinder are also axially rotated. This construction also serves to 40 maintain the sleeve and cylinder in proper relation with respect to each other for the ports thereof to properly coöperate in the performance of their function, that is, axial displacement of the sleeve and cylinder relatively to each other is prevented. Where it 45 is desired to axially rotate the tool, its shank may be suitably connected to the bore of the cylinder end in which it works, as for instance by a key or spline 53. It will be seen that the axial rotation of the cylinder and sleeve is independent of any movement of the casing and the piston and its operating 50 connections.

In Fig. 2, I have shown the piston actuated by a crank construction indicated generally by reference sign A, said crank construction being arranged within the casing B, to which crank device a piston rod C, is connected, said piston rod being suitably 60 connected to the piston to operate the latter. I do not claim herein the specific construction of crank connection shown, as the same forms the subject matter of another application executed of even date herewith. As 65 above stated, however, the piston may be

operated, so far as the present invention is concerned, by any suitable or convenient driving mechanism.

The device, if desired, and to facilitate the handling thereof, may be provided with 70 a suitable handle D, by which it may be held and manipulated.

While I have shown and described specific details of structure and arrangement, I wish 75 it to be understood, that my invention, in its broadest scope, as defined in the claims, is not to be limited or restricted to specific details. But,

Having now set forth the object and nature 80 of my invention and various constructions embodying the principles thereof, what I claim as new and useful and of my own invention and desire to secure by Letters Patent is:—

1. In a device of the kind described, a 85 cylinder, a piston and a plunger mounted to reciprocate therein in line with each other, means for reciprocating the piston, said cylinder having a series of normally open ports spaced apart from each other in the direction of the length of the cylinder and located between the plunger and piston when in their extreme displaced positions with respect to each other, and means for closing said ports in successive order to any 90 desired extent or succession.

2. In a device of the kind described, a 95 cylinder, a piston and a plunger mounted to reciprocate therein in line with each other, means for reciprocating the piston, said cylinder having a series of normally open ports spaced apart from each other in the direction of the length of the cylinder and located between the plunger and piston when in their extreme displaced positions with respect to each other, and a member 100 slideable longitudinally of the cylinder operating to close said ports in successive order to any desired extent of succession.

3. In a device of the kind described, a cylinder, a piston adapted to reciprocate in the rear end of the cylinder, a plunger also adapted to reciprocate in the cylinder, at the forward end thereof, the cylinder having a port at its forward end leading to atmosphere, means for reciprocating the piston, said cylinder having intermediate its ends and intermediate the plunger and piston when in their extreme displaced positions relative to each other, a series of normally open ports spaced apart from each other in the direction of the length of the cylinder, and a spring resisted member slideable longitudinally of the cylinder to close said ports in and to any desired extent of succession.

4. In a device of the kind described, a cylinder, a piston and a plunger mounted to reciprocate therein in line with each other, means for reciprocating the piston, said cylinder having a series of normally open ports

spaced apart from each other in the direction of the length of the cylinder and a sleeve surrounding said cylinder and slideable longitudinally thereon, for closing said ports in and to any desired extent of succession.

5. In a device of the kind described, a cylinder, a piston and a plunger therein in line with each other, means for reciprocating the 10 piston, said cylinder having a series of ports spaced apart from each other in the direction of the length of the cylinder and adapted to be covered and uncovered by the piston in its reciprocation, said ports being of 15 respectively increasing size, and means for covering and uncovering the ports outside of the cylinder.

6. In a device of the kind described, a cylinder, a piston and a plunger mounted to reciprocate therein in line with each other, 20 means for reciprocating the piston, said cylinder having a series of sets of normally open ports, each set comprising a plurality of ports circumferentially of the cylinder, 25 the said sets being spaced apart from each other in the direction of the length of the cylinder and means for closing said sets of ports in and to any desired extent of succession.

30 7. In a device of the kind described, a cylinder, a piston and a plunger mounted to reciprocate therein in line with each other, means for reciprocating the piston, said cylinder having a series of sets of ports, 35 the said sets being spaced apart from each other in the direction of the length of the cylinder and adapted to be covered and uncovered by the piston in its reciprocation and each set comprising a plurality of ports 40 disposed transversely around the cylinder, and means for covering and uncovering the ports outside of the cylinder, said means comprising a sleeve member provided with openings adapted to register with the several 45 ports of the cylinder and having also passages connecting the several openings.

8. In a device of the kind described, a 50 casing, driving means within the casing, a cylinder mounted for free axial rotative movement relatively to the casing, and having ports through the wall thereof, a piston connected to the driving means and adapted to reciprocate within the cylinder at one end, a member adapted to reciprocate with 55 in the cylinder at its other end and a sleeve surrounding the cylinder and keyed thereto, said sleeve movable endwise to cover and uncover said ports.

9. In a device of the kind described, a 60 casing, driving means within the casing, a cylinder mounted for axial rotative move-

ment relatively to the casing, a piston connected to the driving means and adapted to reciprocate within the cylinder, a plunger also adapted to reciprocate within the cylinder in line with the piston, said cylinder having a series of ports spaced apart from each other in the direction of the length of the cylinder and intermediate the piston and plunger when in their positions of greatest separation, and a sleeve surrounding the cylinder and keyed thereto but slideable longitudinally thereon, for closing said ports in and to any desired extent of succession.

10. In a device of the kind described, a 75 casing, driving means within the casing, a cylinder mounted for axial rotative movement relatively to the casing, a piston connected to the driving means and adapted to reciprocate within the cylinder, a plunger 80 also adapted to reciprocate within the cylinder in line with the piston, said cylinder having a series of ports spaced apart from each other in the direction of the length of the cylinder, and intermediate the piston and plunger when in their positions of greatest separation, a sleeve surrounding said cylinder and keyed thereto but slideable longitudinally thereon, for closing said ports in and to any desired extent of succession, and 85 means to yieldingly retain said sleeve in position to open said ports.

11. In a device of the kind described, a cylinder and a piston mounted to reciprocate therein, means for reciprocating said 95 piston, a plunger also mounted to reciprocate freely in said cylinder, said piston operating to alternately rarefy and compress the air in the space in the cylinder between the piston and plunger to actuate the latter 100 without contacting therewith.

12. In a device of the kind described, a cylinder and a piston mounted to reciprocate therein, means for reciprocating said piston, a plunger also mounted to reciprocate freely 105 in said cylinder, said piston operating to alternately rarefy and compress the air in the space in the cylinder between the piston and plunger to actuate the latter without contacting therewith, and means to confine 110 air in said space, and means to vary the volume of said air, thereby varying the rarefying and compressing action of the piston thereon.

In testimony whereof I have hereunto set 115 my hand, in the presence of the subscribing witnesses, on this 29th day of April, A. D. 1911.

LOUIS E. GOLLY.
